[57] CLAIM

The ornamental design for a lighted portable toiletry case, as shown and described.

DESCRIPTION

FIG. 1 is a perspective view of a lighted portable toiletry case showing my new design;
FIG. 2 is a front elevation thereof;
FIG. 3 is a rear elevation thereof;
FIG. 4 is a right side elevation, the opposite side being identical thereto;
FIG. 5 is a top plan view thereof;
FIG. 6 is a bottom plan view thereof; and,
FIG. 7 is a partial perspective view thereof with the compartments in open condition.
